UNITED STATES PATENT OFFICE

169,982

TRACTOR

Arthur J. Lewis, Stratford, Conn., assignor to The
 Baird Machine Company, Stratford, Conn., a
 corporation of Connecticut

Application January 31, 1951, Serial No. 14,051

Term of patent 14 years

(Cl. D14—3)

To all whom it may concern:

Be it known that I, Arthur J. Lewis, a citizen of the United States, residing at Stratford, county of Fairfield, State of Connecticut, have invented a new, original, and ornamental Design for a Tractor, of which the following is a specification, reference being had to the accompanying drawings, forming a part hereof.

Fig. 1 is a top plan view of a tractor, showing my new design,

Fig. 2 is a side elevation thereof,

Fig. 3 is a front view, and

Fig. 4 is a perspective view looking toward the left side of the tractor.

This application is a continuation in part of my prior application Serial No. D. 147,480, filed July 9, 1948, for Design for a Tractor, now abandoned.

I claim:

The ornamental design for a tractor, substantially as shown.

ARTHUR J. LEWIS.
